[57] CLAIM

The ornamental design for a plant support, as shown and described.

DESCRIPTION

FIG. 1 is a perspective drawing showing front, rear, side and top views of a number of my plant supports arranged with interconnecting rods to support a plant and wherein the matter shown in dashed line comprises no part of the invention;

FIG. 2 is a perspective drawing in enlarged view showing front and top views of the vertical stake;

FIG. 3 is a plan drawing in a more enlarged view showing a rear view of the vertical stake; and,

FIG. 4 is a drawing showing a top view of the ground plate and wherein the bottom view is identical.

The plant stake(s) are shown fragmented to indicate indeterminate length.
